Primary Examiner — Cathron Brooks(74) Attorney, Agent, or Firm — McAndrews, Held & Malloy, Ltd.(57) CLAIM

The ornamental design for a bed, as shown and described.

DESCRIPTION

FIG. 1 is a front elevation view of a bed showing our new design;

FIG. 2 is a left side elevation view thereof; the right side elevation view being a mirror image thereof; and,
FIG. 3 is a top plan view thereof.

The broken lines shown in the drawings illustrate portions of the bed that form no part of the claimed design.
